WEATHER STRIP DEVICE

Amsey Crill, Ontario, Oreg.

Application August 21, 1939, Serial No. 291,256

2 Claims. (Cl. 20—68)

My invention relates to a weather strip construction and has as one of the principal objects thereof the provision of a construction or device of the above described character for effectively sealing window sashes within window frames to preclude the passage of air currents through the clearance space therebetween.

Another object of my invention is to provide a device of the above described character which is simple in construction, durable in use, efficient in operation and economical in manufacture.

Other objects and advantages will be apparent from the following description, appended claims and annexed drawings.

Referring to the drawings wherein like reference characters designate like parts throughout the several views:

Figure 1 is a transverse sectional view of a window frame illustrating a pair of sashes arranged therein, the latter being partially illustrated in section.

Figure 2 is a sectional view taken on the line 2—2 of Figure 1.

Figure 3 is a sectional view taken on the line 3—3 of Figure 1.

Figure 4 is a fragmentary perspective view of a lower corner of a window sash illustrating my invention as applied thereto.

Figure 5 is a detail perspective view of one side of a window sash and illustrating my invention as applied thereto and in disassembled relation.

In practicing my invention, as illustrated in the drawings, I provide a window frame 5 in which are slidably mounted upper and lower sashes 6 and 7 respectively. The frame is fashioned with side, top and bottom frame-pieces or members 8, 9 and 10 respectively which are provided with grooves or channels accommodating the sash rails of the sashes. The foregoing is descriptive of a window frame and sashes of an ordinary construction and forms no part of the present invention per se.

The side end faces of the sashes have attached thereto elongated strips or members 11 fashioned between their sides with inwardly extending ribs 12 disposed within grooves 13 formed in the respective rails. The ribs 12 are fashioned with lengthwise extending grooves or channels 14 and slidably receive therein ribs 15 formed on adjacently arranged elongated companion members 16.

The companion members 16 are provided with side sections bent upon themselves and which terminate in right angularly arranged portions constituting the ribs 15. The upper and lower

ends of the members 16 are fashioned with right angularly disposed flanges overlying and underlying the upper and lower rails of the sashes with the upper flanges connected thereto by means of screws 17 extending through elongated slots in said upper flanges whereby to permit lateral movement of the members 16 with respect to the members 11. The outer faces 18 of the members 16 are adapted to slidably engage the faces of the side frame-pieces 8 within the channel as clearly illustrated in Figure 3 of the drawings. Interposed between the members 11 and 16 and between the ribs 15 are elongated resilient strips or elements 19, one end of each being connected to the adjacent end of a respective member 11 by means of a nail or the like 20. The elements 19 are transversely corrugated and coact with members 11 and 16 to maintain the members 11 spaced with respect to the adjacent members 16 and to effect engagement of the faces 18 with the faces of the side frame-pieces and thereby effect a seal between the side sash rails and the side frame-pieces 8.

The upper and lower sash rails of the upper and lower sashes respectively are recessed and each accommodates therein an elongated member 21 formed with a lengthwise extending and centrally disposed arcuate-shaped groove 22 disposed in a channel 23 formed in the respective rail. Adjacent the members 21 the top and bottom frame members 9 and 10 have attached thereto by means of nails 24 or the like elongated companion members 25 each fashioned with a lengthwise extending arcuate-shaped groove 26 defining an arcuate-shaped rib 27 disposed within the groove 22 and coacting with the wall of the latter to effect a seal between the members. Obviously, when the sashes are operated to closed position, as illustrated in Figure 1, the rib 27 seats within the groove 22 and effects a seal between the members, thereby precluding the admittance of air between the sashes and window frame.

From the foregoing it will be apparent that I have provided a simple and efficient device capable of being attached to window constructions without materially modifying the latter and which serves as an effective means for precluding the passage of air currents between the sashes and frame-pieces when the sashes are in closed position.

It is obvious that the invention is not confined to the herein described use therefor as it may be utilized for any purpose to which it is adaptable. It is therefore to be understood that the invention is not limited to the specific construction as

illustrated and described, as the same is only illustrative of the principles of operation, which are capable of extended application in advance forms, and that the invention comprehends all construction within the scope of the appended claims.

What I claim is:

1. A weather strip construction, comprising an elongated member secured to the side edge of a sash and provided with two spaced longitudinally extending ribs formed with grooves opening outwardly and entering grooves in the sash, a second elongated member having laterally turned ends extending over the upper and lower ends of the sash, ribs carried by the said last mentioned member and entering the longitudinally extending grooves in the first mentioned member, and an elongated corrugated spring secured to the first mentioned member between the grooves and

adapted to normally force the second mentioned member outwardly.

2. A weather strip construction, comprising an elongated member secured to the side edges of a sash and provided with two spaced longitudinally extending ribs formed with grooves opening outwardly and entering grooves in the sash, a second elongated member having laterally turned ends extending over the upper and lower ends of the sash and one of said laterally turned ends having a slot receiving securing means carried by the sash, ribs carried by said last mentioned member and entering the longitudinally extending grooves in the first mentioned member, and an elongated corrugated spring secured at one end to the first mentioned member between the grooves and adapted to normally force the second mentioned member outwardly.

AMSEY CRILL.
